UNITED STATES PATENT OFFICE.

JOHN SHIELDS, OF HANCOCK, MICHIGAN.

LOCOMOTIVE-CAB WINDOW.

SPECIFICATION forming part of Letters Patent No. 276,907, dated May 1, 1883.

Application filed December 23, 1882. (No model.)

To all whom it may concern:

Be it known that I, JOHN SHIELDS, of Hancock, in the county of Houghton and State of Michigan, have invented certain new and useful Improvements in Windows for Locomotive-Cabs; and I do hereby declare that the following is a full, clear, and exact description of the invention, which will enable others skilled in the art to which it appertains to make and use 10 the same, reference being had to the accompanying drawings, which form a part of this specification, and in which—

Figure 1 is a perspective view of my improved window for locomotive-cabs, and Fig. 15 2 is a detail view of the same.

Similar letters of reference indicate corresponding parts in both the figures.

My invention has relation to windows for locomotive-cabs; and it has for its object to provide a window which may be opened, so as to enable the engineer to have a free lookout along the track, and at the same time protect him against the weather and smoke and cinders from the engine, while it may be slid forward, if desired, in the manner usual in this 25 class of windows, leaving the window entirely free and open. To this end I make a window of a construction set forth in the following description, and pointed out particularly in the 30 claims.

In the accompanying drawings, the letter A indicates part of the cab-frame, which is provided with a fixed window, B, and a sliding frame, C, sliding in ways D of the frame, and 35 in which is hinged a window, E. The hinges F of this window are sunk into the frame, so as not to interfere with the sliding of the window and its frame. A bar, G, bent in the end, is hinged to the swinging window E, and its 40 bent end is adapted to engage in a series of staples or bails, H, upon the inside of the bottom piece of frame C. By changing the bent end of bar G from one of these bails to another the swinging window may be opened at 45 any desired angle. Upon the inside of the bottom piece of the frame is a staple, I, adapted

to receive the bent end of bar G, and to hold the sliding frame either closed or slid back in front of the fixed window, while a turn-button or swivel, J, serves to hold the swinging window closed. In this manner it will be seen that the swinging window may be opened at any desired angle, protecting the engineer in looking out, while, when desired to have a perfectly free lookout, or when the engine is 50 passing objects near to the track, which might come in contact with the window, it may be closed and slid forward in its ways in the same manner as windows usually employed in locomotive-cabs. 55

A sector-shaped plate, K, may be hinged to the upper edge of the swinging window in such a manner that it may be extended to cover the opening on top between the swinging window and the sliding sash, forming a protection from 60 objects from above, and be folded down when it is desired to slide the window forward.

Having thus described my invention, I claim and desire to secure by Letters Patent of the 65 United States—

1. The combination, in a window for locomotive-cabs, of the frame A, having horizontal ways D and bail I, sliding frame C, having bails H, and swinging window E, having bent hinged bar G, as and for the purpose shown 70 and set forth.

2. As an improvement in windows for locomotive-cabs, the combination and arrangement, as set forth, of the frame A, having ways D, the fixed window B, sliding frame C, 80 swinging window E, plate K, bails H and I, bar G, and turn-button J, all constructed to operate as and for the purposes shown and specified.

In testimony that I claim the foregoing as 85 my own I have hereunto affixed my signature in presence of two witnesses.

JOHN SHIELDS.
